UNITED STATES PATENT OFFICE.

JAMES A. LOVELAND AND MERRITT L. FISHER, OF KALAMAZOO, MICHIGAN.

LIGHT-DEFLECTOR.

1,399,355.

Specification of Letters Patent.

Patented Dec. 6, 1921.

Application filed March 22, 1920. Serial No. 367,792.

To all whom it may concern:

Be it known that we, JAMES A. LOVELAND and MERRITT L. FISHER, citizens of the United States, residing at Kalamazoo, in the 5 county of Kalamazoo and State of Michigan, have invented certain new and useful Improvements in Light-Deflectors, of which the following is a specification.

This invention relates to new and useful 10 improvements in light deflectors which may be advantageously used in corridors, the aisles of moving picture theaters as pilot lights and the like; the primary object of the invention being to provide a deflector which 15 will cast light from any suitable source down upon the floor so that the glare from the source of light will not annoy one looking down upon the device.

Another important object of the invention 20 is to provide a device of this nature including a body portion which consists of a plurality of downwardly and outwardly flaring deflector members which are maintained in spaced relation whereby the source of 25 light located in the body portion may be passed downwardly thereof.

Another object of the invention is to provide a device of the above nature including a base which may be readily detached from 30 or attached to a suitable light support.

A still further object of the invention is to provide a device which embodies a compact construction which may be subjected to severe usage and still retain its rigidity, 35 and one which is inexpensive to manufacture and highly efficient in practice.

Other objects and advantages of the invention will become apparent during the course of the following description.

40 In the accompanying drawings forming a part of the application and wherein like numerals are employed to designate like parts throughout the several views.

Figure 1 is a side elevation of the invention, parts thereof being broken away to show the assemblage of parts.

Fig. 2 is an enlarged fragmentary section through one side of one of the deflectors and

Fig. 3 is a bottom plan of the top of the 50 deflector.

In the drawings, wherein for the purpose of illustration is shown the preferred embodiment of my invention, the numeral 4 in the present instance designates a circular lamp base upon which is attached a vertically disposed incandescent lamp 5.

The base of the deflector consists of an annular band 6 having oppositely disposed threaded apertures 7 therein for the reception of set screws 8 which are adapted to be 60 screwed into engagement with the lamp base to maintain the band in engagement therewith. The upper marginal edge of the band 6 is equipped with a pair of oppositely disposed inwardly extending ears 9 disposed 65 at right angles to the band, and are apertured for a purpose to presently appear.

The body portion 10 of the deflector housing consists of a plurality of superposed deflector elements 11 each of which consists 70 of a band 11 which flares outwardly and downwardly as is clearly shown. The upper marginal edge of each band or deflector 11 is provided with oppositely disposed inwardly extending ears 12 each of which is 75 apertured as at 13. The apertures through the ears in the deflectors and base band 6 are adapted to align for a purpose which will presently appear.

The cap 14 is an inverted imperforated 80 bowl shaped element the marginal edge of which is provided with oppositely disposed inwardly extending apertured ears 15. These ears are adapted to rest upon the ears 12 of the uppermost deflector 11 whereby a 85 bolt 16 may be passed through the ears 16, 12 and 9 of the top, deflector and base respectively, it being understood that one bolt is used for each series of ears.

In order that the deflector 11 may be 90 spaced one above the other and the lowermost deflector spaced from the base 6, a plurality of spacing sleeves 17 are mounted upon each bolt 16. Each sleeve has its lower end engaging the upper surface of an ear 95 carried by the lower element and its upper end engaging the under surface of an ear carried by one of the deflectors 11. A nut 18 is of course threaded upon the lower end of each bolt 16 and abuts with the under 100 face of an ear 9 to retain all of the parts in the proper position.

From the foregoing description, it will be obvious that such deflectors may be advantageously used in motion picture theaters by 105 placing the deflector over a pilot light located at each aisle, upon steps, or any other place where a person is apt to stumble and fall. Due to the compact and rigid construction of the deflector, parties accidentally bumping into the same will not 110 damage or weaken the construction. It is

also obvious that the deflector may be readily disengaged from the lamp base by loosening the set screws and lifting the deflector from the lamp base.

- 5 The foregoing description and the drawings have reference to what may be considered the preferred form of my invention. It is to be understood that I may make such changes in construction and arrangement 10 and combination of parts, material, dimensions, et cetera, as may prove expedient and fall within the scope of the appended claims.

Having thus fully described our invention, what we claim as new and desire to secure by 15 Letters Patent is:—

1. A device of the class described comprising a body portion including a plurality of superposed spaced deflectors, a source of light within the body portion, each deflector 20 having an inwardly extending apertured portion, and means extending through said apertured portions of the deflectors for securing them in position.
2. A device of the class described comprising an annular band provided with an inwardly extending apertured portion, a 25

plurality of superposed spaced deflectors above the band and having inwardly extending apertured ears, rods, extending through the openings in the apertured portion and 30 ears, and spacing elements on the rods to space the deflectors apart and the lowermost deflector above the band, the lowermost spacing element resting upon the inwardly extending portion of the band.

3. A device of the class described comprising a base, a top having apertured ears, a body portion consisting of a plurality of superposed outwardly flaring spaced deflectors, each of which and the base is provided 40 with apertured ears, spacing elements between the ears and deflectors and base, and means extending through said ears and spaced elements for securing the parts together.

45 In testimony whereof we affix our signatures in presence of two witnesses.

JAMES A. LOVELAND.
MERRITT L. FISHER.
